PROCESS FOR THE TREATMENT OF PETROLEUM DISTILLATES

Bernard Laine and Charles Vernet, Lavera par Martigues, Bouches-du-Rhône, France, assignors to The British Petroleum Company Limited, London, England, a British joint-stock corporation

No Drawing. Filed Oct. 26, 1960, Ser. No. 64,986
Claims priority, application France Oct. 26, 1959

11 Claims. (Cl. 208—264)

This invention relates to the treatment of distillate petroleum fractions boiling above 150° C. and particularly to the treatment of distillates boiling between 150 and 450° C., such as 150–250° C., 250–350° C. and 350–450° C. distillates, and the principal object of the invention is to provide a process by means of which the pour point and cloud point of such fractions may be substantially lowered.

According to the process of the present invention, the distillate is contacted in the presence of hydrogen with a catalyst having dehydrogenating and/or cracking activity and comprising a silica-alumina base, at a temperature of at least 400° C. but below the temperature at which substantial cracking occurs, a pressure of at least 100 p.s.i.g., and a space velocity of the liquid feedstock not exceeding 3.0 v.v./hr., the temperature and space velocity being correlated so that the pour point of the stabilized distillate is at least 5° C. lower than the pour point of the feedstock.

For the purposes of the present specification, substantial cracking is understood to occur when more than 20% wt. of the feedstock is converted to material boiling below 150° C. Preferably not more than 15% wt. of the feedstock is converted to material boiling below 150° C. The temperature employed will not usually exceed 480° C. and in general the lower the temperature, the lower the space velocity.

The pressure employed will normally be between 100 and 1500 p.s.i.g. and the hydrogen to hydrocarbon mole ratio will normally be from 5 to 1 to 20 to 1.

In general, it is preferred to operate under conditions which result in an overall consumption of hydrogen, since such method of operation increases catalyst life, and to achieve such overall consumption of hydrogen it is necessary to operate at a pressure above the equilibrium pressure of the feedstock, i.e. the pressure obtainable by recycling the hydrogen produced at a particular combination of temperature and space velocity, no extraneous hydrogen being added after start-up.

A further advantage of operating with an overall consumption of hydrogen is that a reduction of the diesel index is minimized or avoided.

In some cases, however, it may be desired to reduce the pour point of the distillate without substantially reducing its specific gravity, and in these cases it is necessary to operate under conditions in which no hydrogen is consumed, i.e. at or below the equilibrium pressure as defined above.

Hydrogen may be added on a once-through basis, or it may be recycled.

The distillate fraction used as feedstock may have a low initial sulfur content, for example 0.1% wt. sulfur or less. Such low sulfur feedstocks may be straight-run materials or the products of previous refining treatments, for example, products of a hydrocatalytic desulfurization process. With feedstocks containing higher amounts of sulfur, the process according to the invention may result in a considerable reduction in the sulfur content. In the case of feedstocks having a low initial sulfur content, the process may be accompanied by an increase in specific gravity.

2

Some lower boiling material will be produced by, for example, dehydrogenation, desulfurization and/or a small amount of cracking, and this is separated from the product, preferably by fractionation, to stabilize it and give a material of the required boiling range and flash point. A convenient cut point is in the region of 130–170° C.

Particularly effective catalysts for the purposes of the present invention consist of molybdenum trioxide, MoO_3 , supported on a silica/alumina base, and a mixture of molybdenum trioxide, MoO_3 , and cobalt oxide, CoO , supported on a silica/alumina base.

It has been found that the presence of cobalt oxide, CoO , is not necessary for achieving the desired reduction of the pour point but is essential if simultaneous desulfurization of the feedstock is required. Thus, in treating a sulfur-free feedstock or in treating a sulfur-containing feedstock when it is not necessary to remove sulfur, a particularly effective catalyst may have the following composition by wt.

	Percent
Molybdenum trioxide, MoO_3	5–15
Silica, SiO_2	5–14
Alumina	Balance

When it is desired to desulfurize the feedstock as well as reduce its pour point, the catalyst may have the following composition by weight:

	Percent
Molybdenum trioxide, MoO_3	5–15
Cobalt oxide, CoO	.2–1
Silica, SiO_2	5–14
Alumina	Balance

The optimum content of molybdenum trioxide appears to be 10–11% and the optimum molar ratio of the metals Co to Mo appears to be .1.

The ratio of cobalt to molybdenum necessary to produce the desired reduction in the sulfur content is considerably less than in the case of conventional cobalt molybdate catalysts used for desulfurization. This may be due to the fact that more severe process conditions, i.e. higher temperature and pressure and lower space velocity, are required to produce the desired reduction in the pour point.

It has been found that the use of a catalyst having a silica/alumina base enables a particular reduction in pour point to be effected at a lower temperature than is possible with a catalyst supported on an alumina base. The use of lower temperatures means that it is possible to use a lower hydrogen to hydrocarbon ratio, thereby reducing the cost of the process.

Experiments were carried out with four catalysts having the following compositions by weight.

Catalyst No. 1:	Percent
MoO_3	14.4
CoO	1.9

On a base consisting of 95% Al_2O_3 and 5% SiO_2 .

Catalyst No. 2:	Percent
MoO_3	14.4
CoO	1.9

On a base consisting of 90% Al_2O_3 and 10% SiO_2 .

Catalyst No. 3:	Percent
MoO_3	12.0
CoO	3.6

On a base consisting of silica-free alumina.

These catalysts were used to treat a gas oil having a sp. gr. of 0.850 and a pour point of -1°C . under the following conditions.

Temperature (catalysts Nos. 1 and 2) 420, 440 and 450° C.
 Pressure (catalyst No. 3),
 40 kg./cm.² 420, 450 and 480° C.
 Space velocity 1 v./v./hr.
 Hydrogen to hydrocarbon ratio 10/1.

The results obtained are set out in the following table, No. 1, which includes the properties of the feedstock.

It can be seen from the results set out in Table 1 that the catalysts which included silica in the support enabled a significant reduction of the pour point to be obtained at a temperature as low as 420° C. while the catalyst based on silica-free alumina had to be used at 480° C. to obtain a result equivalent to that obtained at 440° C. using the catalyst based on silica-containing alumina.

In order to maintain the hydrogen partial pressure at the desired level, it is necessary progressively to increase the total pressure since the reaction produces gas and consumes hydrogen.

- 5 Satisfactory operation over a period of 600 hours has been achieved on the light gas oil at a constant total pressure of 780 p.s.i. since, as the hydrogen consumption was small, the hydrogen partial pressure fell only from 570 to 500 p.s.i.
 10 On the other hand, when treating the heavy gas oil at a fixed total pressure of 1000 p.s.i., the hydrogen partial pressure fell from 800 p.s.i. to 550 p.s.i. after 420 hours and pour conversion was then obtained at 460° C. Improved operation may be achieved by maintaining the hydrogen partial pressure at 800 p.s.i. by progressively

² Method AFNOR N.F.T. 60.105.

³ Method AFNOR N.F.M. 07.009.

The catalyst may be employed as a fixed bed, a moving bed, or in the fluidized state.

The degree of reduction in pour point is a function of the catalyst activity and in the case of a fixed bed process, in which the catalyst is not continuously regenerated, the greatest reduction in pour point is obtained during the early stages of a processing period. In such circumstances, the operating temperature may be gradually increased to compensate for loss of activity. Alternatively, continuous catalyst regeneration may be employed, using either a moving or fluidized catalyst bed process.

If desired, a part only of a particular distillate may be treated by the process according to the invention and the resulting product blended with the untreated portion of the distillate to give a final product of reduced pour point.

It has been discovered that it is desirable to maintain a certain hydrogen partial pressure for any particular feedstock and that the degree of conversion falls off if the hydrogen partial pressure falls below this minimum even if the total pressure is maintained. The optimum values for the hydrogen partial pressure and the hydrogen to hydrocarbon ratio depend upon the nature of the feedstock. For example, these conditions are compared in the following table, No. 2, for a light gas oil having an I.B.P. of 220° C., an F.B.P. of 400° C. and a pour point of -1° C. and a heavy gas oil having an I.B.P. of 290° C., an F.B.P. of 390° C., and a pour point of +17° C.

Table 2

	H ₂ /H ₂ Ratio	Partial Pressure of Hydrogen, p.s.i.
Light Gas Oil	5-8	570
Heavy Gas Oil	8-15	800

increasing the total pressure and this effect is illustrated by the results set out in Table No. 3.

40 Satisfactory treatment of a heavy gas oil at constant pressure may be achieved by adding between 20 and 100% by volume of a lower boiling distillate such as kerosine to the heavy gas oil. An example of this method of operation is illustrated by the results set out in Table No. 4.

45 A silica-alumina base suitable for preparing a catalyst for use in accordance with the present invention may be made in a variety of ways.

According to one method, the silica gel is precipitated 50 in situ in the pores of the alumina by hydrolyzing a silicon compound with which the alumina is impregnated. The silicon compound may be organic or inorganic and suitable compounds include ethyl silicate, trichlorosilane and tetrasilane. It is advantageous to add to the ethyl silicate, 55 for example, a sufficient quantity of alcohol to saturate the alumina almost completely to ensure homogeneous distribution of the silicate in the alumina. Ethyl, methyl and other alcohols may be used for this purpose. Finally, the silicate is hydrolyzed by means of acidified water and 60 the formation of the gel assisted by the addition of ammoniacal water. The silica-alumina composite is then dried and calcined. The following is a specific example of preparing a silica-alumina base by this method:

EXAMPLE

In order to obtain 1,110 g. of a support having 10% silica, a solution was prepared containing 330 g. of ethyl silicate (30% SiO₂) and 150 cc. of methanol. 1 kg. of alumina granules calcined between 200 and 800° C. were 70 slowly wetted with this solution while stirring and after several minutes to allow homogeneous impregnation, the granules were washed with 100 cc. of water containing 10% HCl. After several hours, the granules were washed with 100 cc. of ammoniacal water and then calcined at 75 about 450° C.

The results obtained on treating a heavy gas oil using catalysts having bases prepared by the method just described are set out in Table 5. This table also illustrates the effect of varying the silica content of the base. It will be seen that the results obtained with a 20% silica base are markedly inferior to those obtained with a 15% silica base and in general it has been found that the content of silica should not exceed 14% by weight of the total catalyst.

25 A more economic method of preparing a suitable silica-alumina base consists in extruding an intimate mixture of silica gel and alumina. The silica may be prepared in known manner from sodium silicate and is washed with sulfur acid to remove sodium. The silica gel is then 30 mixed with the alumina and the mixture extruded to form extrudates of between 2 and 2.75 mm. diameter. Two particularly effective catalysts prepared in this way had the following percentage compositions by weight.

	Catalyst 1	Catalyst 2
Silica	8.9	13.3
MoO ₃	10.7	10.7
CoO	0.5	0.5
Alumina	balance	balance

Various results obtained using catalysts having bases prepared in the manner just described are set out in Tables 6, 7 and 8.

It is important for the temperature and space velocity to be correctly correlated if a satisfactory reduction in 45 the pour point is to be achieved. Thus, even a silica-alumina based catalyst will not give satisfactory results unless the temperature and space velocity are correctly correlated. For example, the use of such a silica-alumina based catalyst under conditions of temperature, pressure and space velocity conventionally used in hydrocatalytic desulfurization processes gives no reduction at all in the pour point. The results set out in Table 9 illustrate this point, the catalyst used having a base of 10% silica and 50 90% alumina.

What we claim is:

1. A process for the treatment of distillate petroleum fractions boiling within the range 150-450° C. to lower the pour point at least 5° C. without material reduction in the specific gravity and diesel index of said distillate fractions, comprising contacting the distillate fraction as feedstock in a treating zone and in the presence of hydrogen with a dehydrogenation catalyst on a silica-alumina base whose silica content is in the range 5 to 14% by weight of total catalyst, the hydrogen to hydrocarbon mole ratio being from 5 to 1 to 20 to 1; maintaining a selected temperature and a selected space velocity in said zone, said selected temperature in said zone being maintained at least about 400° C. but not higher than about 480° C. and being a temperature at which, at said selected space velocity, not more than 20% wt. of the feedstock is converted to material boiling below 150° C. and said selected space velocity being at least equal to the space velocity at which at said selected temperature not more than 20% wt. of the feedstock is converted to material boiling below 150° C. but not exceeding 3.0 v./v./hr.; maintaining a selected pressure in said zone in the range 100-1500 p.s.i. ga., said selected temperature and said selected space velocity being correlated to reduce the pour point of the feedstock such that the pour point of the material of the treated distillate fraction boiling above 150° C. is at least 5° C. lower than the pour point of the feedstock, and recovering the treated distillate fraction.

2. A process according to claim 1, wherein the temperature within said temperature range is such that not more than 15% wt. of the feedstock is converted to material boiling below 150° C.

3. A process according to claim 1, wherein the feedstock consists of a heavy gas oil in admixture with 20 to 100% by volume of a lower boiling distillate such as kerosine.

4. A process according to claim 1, wherein the silica content has been derived from a silicon compound with which the alumina has been impregnated.

5. A process according to claim 4, wherein said silicon compound is ethyl silicate.

6. A process according to claim 1, wherein the silica-alumina base of the catalyst consists of a mixture of pre-formed alumina and silica.

7. A process according to claim 1 wherein the pressure is above the equilibrium pressure of the feedstock at the particular combination of correlated temperature and

space velocity, whereby reduction of the diesel index is at least minimized.

8. A process for the treatment of distillate petroleum fractions boiling within the range 150-450° C. to lower the pour point at least 5° C. without material reduction in the specific gravity and diesel index of said distillate fractions, comprising contacting the distillate fraction as feedstock in a treating zone in the presence of hydrogen with a catalyst consisting essentially of 5-15% by weight of molybdenum trioxide supported on a silica-alumina base, the silica content being in the range 5-14% by weight of total catalyst, the hydrogen to hydrocarbon mole ratio being from 5 to 1 to 20 to 1; maintaining a selected temperature and a selected space velocity in said zone, said selected temperature in said zone being maintained at least about 400° C. but not higher than about 480° C. and being a temperature at which, at said selected space velocity, not more than 20% wt. of the feedstock is converted to material boiling below 150° C., and said selected space velocity being at least equal to the space velocity at which at said selected temperature not more than 20% wt. of the feedstock is converted to material boiling below 150° C. but not exceeding 3.0 v./v./hr.; maintaining a selected pressure in said zone which is greater than the equilibrium pressure of the feedstock at said selected contacting temperature and said selected space velocity but not greater than about 1500 p.s.i. ga., said selected temperature and said selected space velocity being correlated to reduce the pour point of the feedstock such that the pour point of the material of the treated distillate fraction boiling above 150° C. is at least 5° C. lower than the pour point of the feedstock, and recovering the treated distillate fraction.

9. A process according to claim 8, wherein the molybdenum oxide content is 10 to 11%.

10. A process in accordance with claim 8 wherein the catalyst further includes cobalt oxide in an amount of .2-1% by weight with the molybdenum trioxide being present in an amount of 5 to 15%.

11. A process according to claim 10, wherein the molar ratio of the metals Co to Mo is 0.1.
